United States Patent Office

Des. 202,685
Patented Oct. 26, 1965

202,685

DOMESTIC BLENDING APPLIANCE

Douglas N. Cabell, Birmingham, and Alfred J. Prizlow,
Royal Oak, Mich., assignors to Ronson Corporation,
Woodbridge, N.J., a corporation of New Jersey

Filed June 16, 1964, Ser. No. 80,422

Term of patent 14 years

(Cl. D89—1)

Fig. 1.

Fig. 2.

Fig. 3.

Fig. 4.

Fig. 5.

Fig. 6.

Fig. 7.

FIG. 1 is a front elevational view of a domestic blending appliance showing our new design;

FIG. 2 is a rear elevational view;

FIG. 3 is a side elevational view;

FIG. 4 is a top perspective view of the blender jar element;

FIG. 5 is a top perspective view of the motor housing element;

FIG. 6 is a top plan view of the assembled elements; and

FIG. 7 is a bottom perspective view of the blender jar element.

This application is a continuation-in-part of our co-pending application Serial No. 72,838, filed December 13, 1962 and now abandoned.

We claim:

The ornamental design for a domestic blending appliance, as shown and described.
